UNITED STATES PATENT OFFICE

2,499,594

PULL CHAIN PENDANT FOR LAMPS

Nicholas Kulay, New York, N. Y.

Application May 17, 1946, Serial No. 670,398

2 Claims. (Cl. 16—122)

1

This invention relates to pendants, grips or locators for pull chains, for lamps and similar articles, and has for its main object to provide a novel device of this character which will be more efficient than those used for similar purposes at present, at the same time being very simple in construction, inexpensive to manufacture, easy to apply, and still strong and reliable in use.

Another object of this invention is to provide a device, as characterized hereinbefore, which will have several wings with surfaces adapted for advertising or other information to be displayed thereon, or the wings themselves may be formed into a desired display.

Still further objects of this invention will be partly apparent and partly pointed out as the specification of the same proceeds, and, among others, I may mention: to provide a device of this type which will be attractive in appearance, easily grasped when its use is needed, even while the same is placed into various positions, by an air current, or by the action of a fan or the like, and which will rotate under the action of such fan and therefore add to the attractiveness of the same, and additionally call the attention of the observer to the display or advertisement carried by it.

In the drawings forming a part of this specification, and accompanying the same:

Fig. 1 shows a blank to be used for one pair of wings in a preferred embodiment of my invention, and

Fig. 2 is an end view thereof;

Fig. 3 shows a blank by which another pair of wings are formed in the completed device, in co-operation with the blank of Fig. 1;

Fig. 4 is a plan view of a disk used to secure the wings together and keep them in the desired position;

Fig. 5 is a side view of the completed device, and

Fig. 6 is a plan view thereof.

Referring now to the drawings more in detail, by characters of reference, the numeral 10 indicates a blank, in general, cut out of any appropriate sheet material, like cardboard, wood or plastics, having right hand and left hand wing portions 11 and 12, an intermediate portion, generally indicated by the numeral 13, connecting the two wings, and an upstanding central projection 14.

An opening 15 is provided in the lower part of a central or connecting portion 13, whereby a loop member 16 is formed, connecting the lower parts

2

of the two wings 11 and 12, said loop to be used for pulling the device, as will be more fully explained hereinafter.

A vertical central slot 17 is provided in the upward projection 14, to a desired depth thereof, and on the two sides of said slot are arranged holes 18 and 19 into which the pull chain, or cords securing the device to the pull chain, may be inserted.

Fig. 3 shows a companion blank, generally indicated by the numeral 20, having the right hand and left hand wing portions 21 and 22, and an intermediate connecting portion 23 from which is projecting an upward member 24, similar to the upward projection 14 in the blank 10.

As will be more fully shown presently, these two blanks will be secured together perpendicularly to one another, by the use of said slots, whereby a four winged device, illustrated in Figs. 5 and 6, 20 will be produced.

For such securing and keeping the two blanks in said relative perpendicular position, I employ a specially formed disk 26, illustrated in Fig. 4, the disk having communicating, perpendicular, transverse slots 27 and 28 in its center, and two corresponding pairs of slots or incisions 27a and 27b and 28a and 28b, respectively, at the ends of the diameters of the central cross slots 27 and 28. To form my novel pull chain pendant, the blank 20 will be pushed over the blank 10, perpendicularly thereto, by sliding the same through the slot 17 in the blank 10, and then over a portion of the central connecting part 13, indicated by the numeral 29, the slot 25 in said blank 20 engaging said portion 29 of the material of blank 10, while obviously slot 17 in the blank 10, will engage the two sides of the central upward portion 24 of the blank 20.

By these mutual slot and plate material engagements of the two blanks, the same will be placed into the perpendicular position to one another, indicated in Figs. 5 and 6.

To further secure them in this position, and prevent their relative movements, disk 26 will now be placed over the two central projections 14 and 24, respectively, its central cross slots 27 and 28 engaging the respective projections and sliding down thereover, so that said disk 26 will finally come to rest on the shoulders or upper edges 13a and 13b in the central connecting part 13 of the blank 10, and on the shoulders or edges 23a and 23b of the connecting part 23 of blank 20. The outer marginal incisions of slots 27a and 27b and 28a and 28b will engage the respective portions 13c and 13d of the wings 11 and 12 adjacent

to the shoulders 13a and 13b, and the portions 23c and 23d of the wings 21 and 22 adjacent to the shoulders 23a and 23b, respectively.

Small incisions 30 may be made in the material of the upward central projections 14 and 24 at their bases to further lock the disk 26 in its position when the device is assembled.

As has been mentioned, the pull chain or string may be secured into the holes 18 and 19 of the blank or member 10, forming the two wings 11 and 12, or cords 31 may be provided for securing the same device on such a pull chain, as will be understood. The device will hang at the lower end of the pull chain or cord in the position indicated in Fig. 5, and, when it is desired to use it, for instance, for switching on or extinguishing an electric ceiling light, a downward pull, indicated by the arrow 32, will be exerted thereon, preferably by hooking a finger over the loop member 16.

Both surfaces of the four wings 11, 12, 21 and 22, respectively, may be used for advertising, display, information, etc., whereby my device will provide eight such surfaces. It also will be seen that no matter which way a person looks at the device, one of these displays and advertisements may be easily read.

My device, by its novel and very attractive appearance, will call the attention of people to the advertisements or displays carried thereby.

Finally, the wings of my device not only may carry advertisements, etc. but the wings themselves may be formed into any desired shape, like imitating a well-known symbol, person, character, etc.

While I have shown a preferred embodiment of my invention, it is to be understood that changes and variations may be resorted to in the elements and combinations of the same, and I reserve my rights to such changes and variations as are within the spirit of this specification, and the scope of the claims hereunto appended.

What I claim as new, and want to protect by Letters Patent of the United States, is:

1. A pendant for pull chains comprising two winged blanks of sheet material, each blank having an upward projection in its center, a downward slot being provided in about the center of the upward projection of one of the wing blanks, and an upward slot being provided in about the center of the other wing blank from the bottom edge thereof, whereby the two blanks may be

telescopically secured together, the blank with the upward slot sliding down through the downward slot of the other blank, whereby its projection will be engaged in said downward slot of the other blank, and it will engage the material of said other blank by its own upward slot, a circular securing disk, having two center slots transversely crossing one another, said disk being slid over the two upward projections, its respective slots engaging them, and said disk resting on the upper edges of the respective wing blanks, inward marginal diametrical slots from the periphery of said disk in line with the respective central slots, said marginal slots being adapted to engage respective portions of the wing blanks.

2. A pendant for pull chains comprising two winged blanks of sheet material, each blank having an upward projection in its center, a downward slot being provided in about the center of the upward projection of one of the wing blanks, and an upward slot being provided in about the center of the other wing blank from the bottom edge thereof, whereby the two blanks may be telescopically secured together, the blank with the upward slot sliding down through the downward slot of the other blank, whereby its projection will be engaged in said downward slot of the other blank, and it will engage the material of said other blank by its own upward slot, a circular securing disk, having two center slots transversely crossing one another, said disk being slid over the two upward projections, its respective slots engaging them, and said disk resting on the upper edges of the respective wing blanks, an aperture being provided in the central lower part of the wing blank, having the downward slot in its upward projection, whereby a loop will be formed in its lower marginal portion, adapted to exert a pull thereon by that loop, and means to secure 40 said wing blank, having a loop, on the pull chain.

NICHOLAS KULAY.
